UNITED STATES PATENT OFFICE

156,159

DESIGN FOR A CROSS PLATE FOR CYCLE PEDALS

Charles A. Persons, Worcester, Mass.

Application August 23, 1947, Serial No. 141,032

Term of patent 14 years

(Cl. D90—14)

To all whom it may concern:

Be it known that Charles A. Persons, a citizen of the United States, residing at Worcester, in the county of Worcester and State of Massachusetts, has invented a new, original, and ornamental Design for Cross Plate for Cycle Pedals, of which the following is a specification, reference being had to the accompanying drawing, forming part thereof.

Fig. 1 is a top plan view of a cross plate for cycle pedals, showing my new design;

Fig. 2 is a front elevational view thereof;

Fig. 3 is a bottom plan view thereof; and

Fig. 4 is an end elevational view thereof.

I claim:

The ornamental design for a cross plate for cycle pedals, as shown.

CHARLES A. PERSONS.
